UNITED STATES PATENT OFFICE.

WILLIAM INNES, OF NORTHUMBERLAND, ENGLAND, ASSIGNOR TO THE BABCOCK & WILCOX COMPANY, OF BAYONNE, NEW JERSEY, A CORPORATION OF NEW JERSEY.

FLUID HEATER.

Application filed March 19, 1921, Serial No. 453,764, and in Great Britain March 24, 1920.

This invention relates to fluid heaters or economizers applicable to water tube steam generators of the Babcock & Wilcox type and has for its object to provide an improved arrangement of such economizers whereby a better circulation through such economizers, and greater ease in removing sediment with the use of smaller quantities of water than otherwise necessary are obtained.

10 In accordance with the invention the economizer is preferably so arranged that the cold water enters a series of headers from an upper box at one end and leaves by an upper box connected to the series of headers at the 15 other end, a bottom box not directly in the path of normal circulation being also provided for the removal of sediment.

The invention is illustrated in the accompanying drawing which shows in longitudinal section the improved feed water heater and other parts hereinafter referred to applied to a Babcock & Wilcox steam generator of the marine type.

Referring to the drawing, the feed water 25 heater or economizer comprises a number of inclined tubes A connected at their ends to series of uptake and downtake headers B and C, respectively. The headers C are all joined at the top to a box D, the headers B being also 30 all joined at the top to a box E. At the lower end of the headers C is provided a box D', having a blow off connection d'. An inlet pipe, d, preferably fitted with a feed or control valve, is connected to the box D, into 35 which box D the feed water is pumped and from which it passes through the tubes A in which it is heated by the waste gases of combustion on their way to the uptake or chimney, to the box E whence it is led by way of a pipe G, from which it is delivered preferably through a non-return valve H into the steam and water drum F.

Since the lower box D' is not directly in the path of the water circulation, the blowing down may be effected at a point remote from the inlet and the sediment more effectively removed with a smaller quantity of water than would be the case with constructions in which the blow-down valves are fitted to the inlet box and in which, when operated during normal boiler operation, the bulk of the water blown out is supplied direct from the feed pump and is wasted, as it does not remove the sediment from the economizer.

55 The heater or economizer may be located

in any suitable position in the path of the waste gases. In the arrangement shown the heater or economizer is located directly above the generator, with the tubes A slightly inclined to the horizontal, and headers B and C slightly inclined to the vertical, so as to allow the air to get away from the heater or economizer.

The heater or economizer is encased as shown, the casing being provided with access doors I, and is also partially roofed in at J and separated from the boiler furnace K by a horizontal partition L, while baffles M are provided, whereby the gases are caused to follow the path indicated by arrows on their way to the uptake or chimney.

The generator proper which is illustrated as a Babcock & Wilcox boiler, is shown as provided with horizontally inclined generating tubes divided into three spaced banks R, R' and R² connected at one end to uptake headers S, which are in turn connected to the steam and water drum F by horizontal tubes T, the opposite ends of the generating tubes being connected to a downtake header S' nippled to the steam and water drum as at U. The gases are directed across the generating tubes by baffles V, a roof baffle W preferably being disposed above the lower bank R² of the boiler tubes. The superheater is preferably located in the space between the banks R and R' and is shown as extending across the first and second passes of the boiler. The superheater comprises U tubes N extending transversely of the boiler and connected at their ends to headers O, the upper one of which is provided with a transverse diaphragm P, so that the steam flows through the superheater as indicated by the small arrows.

95 In the form of economizer shown there is a circulation of water within the economizer due to the action of the hot gases flowing over the economizer which tends to equalize the temperature of the water throughout the economizer. By supplying feed water to the upper portion of the economizer in the way described the water fed to the economizer is mingled more effectively with the water in the economizer through the action of the circulation caused by the heating action of the gases than it would be should the feed water enter the lower part of the economizer. By supplying feed water to the upper portion of the economizer in the way described the tem- 100 105 110

perature of the water in the upper and lower tubes is therefore much more nearly equalized than in the case of an economizer of the class described in which the feed water is supplied to the lower part of the economizer. Referring to the particular arrangement of economizer with horizontally inclined tubes with uptake and downtake end headers, if the feed water is supplied to the blow-off drum there is a very unequal distribution of heat in the economizer tubes, the water in the lower tubes being much colder than that in the upper ones. This unequal temperature results in unequal expansion between the top and bottom tubes, which causes the tubes to creep somewhat in their seats in the headers, thereby causing the water to leak to the outside, where it comes in contact with soot which may have settled on the tubes, and setting up active external corrosion. I have found, in actual installations, that where the economizer was built in this manner, in some cases the tubes had been corroded through from the outside and that the rear face of the header into which the tubes were expanded had also corroded away so that the seat was thinned down to a dangerous extent. Supplying the feed water to the top of the rear headers has the effect of equalizing the temperature over the whole of the tubes, and from careful readings which I have taken, I have found that the temperature of the water in all of the tubes is very much the same—in practice, I have not found a difference of more than 10 degrees F.—and by constructing the economizer in this manner, I have overcome leakage through the tubes C, so that the soot is kept dry and is readily blown from the tubes.

What I claim and desire to secure by Letters Patent of the United States is:

1. The combination with a steam boiler, of an economizer heated by the gases leaving the boiler, said economizer having vertically extending headers at both ends thereof connected by horizontally disposed tubes, an inlet connection for feeding all of the water supplied to the boiler into the upper ends of

all the inlet headers, an outlet connection for feeding to the boiler the water from the same ends of the outlet headers as it enters the inlet headers, said inlet and outlet headers being unconnected except through said tubes, an economizer setting for receiving the gases from the boiler and directing them over said economizer tubes and in a general direction from the outlet of the economizer towards the inlet thereof.

2. The combination with a steam boiler, of an economizer heated by the gases leaving the boiler, said economizer having vertically extending headers at both ends thereof connected by horizontally disposed tubes, an inlet connection for feeding all of the water supplied to the boiler into the upper ends of the inlet headers at one end of said economizer, and outlet connection for feeding the water from the upper ends of the outlet headers to the boiler, said inlet and outlet headers being unconnected except through said tubes, and an economizer setting for receiving the gases from the boiler and directing them over the tubes of said economizer.

3. The combination with a steam boiler, of an economizer heated by the gases leaving the boiler, said economizer having vertically extending headers at both ends thereof connected by horizontally disposed tubes, an inlet connection for feeding all of the water supplied to the boiler into the upper ends of the inlet headers of said economizer, an outlet connection for feeding the water from the upper ends of the outlet headers at the other ends of the economizer to the boiler, said inlet and outlet headers being unconnected except through said tubes, an economizer setting for receiving the gases from the boiler and directing them over the tubes of said economizer and in a general direction from the outlet of the economizer towards the inlet thereof, and a blow-off connected to the lower part of the economizer.

In testimony whereof I have hereunto signed my name:

WILLIAM INNES.
